DEFROSTING TUNNEL

Walter L. Gibboney, Denver, Colo.

Application September 8, 1944, Serial No. 553,207

4 Claims. (Cl. 134—125)

1

This invention relates to the production and conditioning for distribution of chilled or frozen commodities, such as ice cream, ices, and the like, and more particularly to that phase or step of such production and conditioning which involves separation of a block of chilled or frozen material from the container wherein formed, and has as an object to provide improved means automatically operable as a supplement to and incident of routine production procedure to disrupt the bond, 10 between the block of material and its container and thereby release said block for convenient separation from its matrix.

A further object of the invention is to provide improved means susceptible of convenient incorporation into the production cycle of chilled or frozen commodities to initially detach and thereby facilitate removal of a block of gelid material from its mould.

A further object of the invention is to provide improved means for automatically defrosting a gelid material mould or matrix as an incident of traverse therethrough.

A further object of the invention is to provide improved defrosting means operable to minimize handling and contamination of gelid material within a production and conditioning cycle.

A further object of the invention is to provide a defrosting tunnel adapted for operative association with typical production apparatus, arranged for automatic traverse of the units to be defrosted therethrough, which is simple and inexpensive of manufacture, installation, and maintenance, and which is productive of sustained high quality of product, reduced waste, and economy of labor.

With the foregoing and other objects in view, my invention consists in the construction, arrangement, and combination of elements herein-after set forth, pointed out in my claims, and illustrated by the accompanying drawing, in which—

Figure 1 is a side elevation of the improvement as constructed, assembled, and arranged for practical use, a removable cover element for the assembly being omitted from the showing and certain portions being broken away to illustrate otherwise concealed construction. Figure 2 is a plan view of the showing of Figure 1. Figure 3 is a cross-section, on an enlarged scale, taken on the indicated line 3—3 of Figure 1, lower portions of the assembly being broken away to conserve space and the removable cover being shown in cooperating relation with the other elements of the unit.

In the production of chilled or frozen food com-

2

modities, it is customary practice to finally chill and set the material in pan-like moulds or forms of uniform size, from which containers the blocks of material are subsequently released for conversion into wrapped or packaged units suitable for merchandising. The moulds wherein the material is set, and frequently stored, are generally flat, open-top, rectangular pans of suitable moisture-resistant, heat-conductive material, such as metal, glass, plastic, and the like, whereto the molded food composition adheres and strongly bonds at low temperatures, thereby complicating the operation of removing the molded block from its container. Since separation of the molded block from its matrix is usually desired immediately prior to division, wrapping, and packaging of the block material, it is convenient to introduce into the conveying system feeding the cutting, wrapping, and packaging means a defrosting tunnel wherethrough the molds and their chilled contents may be automatically passed for disruption of the bond adhering the molded blocks to their respective containers, and the instant invention is directed to the provision of a simple and efficient arrangement constituting such a tunnel.

In the construction of the improvement as shown, the numeral 10 designates a relatively-long, open-top, preferably rectangular tank of appropriate size and any desired suitable construction, supported, as by means of fixedly-associated legs 11, or otherwise, in longitudinal alignment and coplanar relation of its upper margins with the upper run of a belt conveyer 12, or equivalent feeding means. The proximate end of the tank 10 is preferably spaced somewhat from the end of the conveyer 12 and a plane, smooth-surfaced shelf 13 fixedly extends from and longitudinally of said tank in the plane of the tank upper margins and the conveyer upper run to bridge the space between the adjacent tank and conveyer ends and function as a slide connecting therebetween. Similarly, a plane, smooth-surfaced shelf 14 fixedly extends in the plane of the tank upper margins from the end of said tank opposite to the shelf 13, and said shelf 14 may, if desired, operatively align and register with conveying or processing means, not shown. The open-top length of the tank 10 thus embraced between the shelves 13 and 14 is longitudinally traversed by a slide-track 15, of operatively-suitable width somewhat less than the width of the open tank top, which smoothly merges at its ends with the shelves 13 and 14, and the upper surface of said slide-track 15 is depressed and gradually inclined

downwardly beneath the plane of the tank upper margins from its junction with the shelf 13 to a low point adjacent and spaced inwardly of the tank end adjoined by the shelf 14, from which low point the said slide-track then rises at a relatively steeper incline to merge with the plane of said shelf 14, the more steeply rising length of said slide-track preferably being intersected by a plurality of apertures or holes 16.

Suitably secured at their opposite ends to and rising above the upper surfaces of the shelves 13 and 14, a pair of guide bars 17 is disposed to bridge longitudinally of the open top of the tank 10, said bars being of a size and construction conducive to rigidity, of such length as will extend well beyond each end of the tank and partially across the shelves 13 and 14, and positioned in such parallel spacing as will freely accommodate the width of a typical mold or container 18 therebetween. The bars 17 serve to define a passage for a mold or container 18 longitudinally traversing the tank 10 upper portion in sliding engagement with the slide-track 15, and for such purpose said bars may conveniently align with side margins of said slide-track, corresponding ends of said bars preferably diverging outwardly and away from the tank 10 to facilitate engagement of successive molds and containers 18 in guided relation therewith.

The tank 10 is adapted and arranged to be maintained charged with heated water to a uniform level such as will normally cover the lower portions of the slide-track 15, and for such purpose said tank is preferably included in a water circulating system whereof the line 19 leads from a suitable source or supply of water, not shown, to and for inflow of water within the tank 10, and the line 20 connects with an upper portion of said tank and opens therethrough at the desired water level therein to provide an outflow from said tank positioned and arranged, as through the use of a line 20 larger than the line 19, to prevent overflow of said tank other than through said line 20. Where hot water supply is available, the water delivered through the line 19 may be pre-heated to the degree desired, or other means, such as heating coils, burners, and the like, such as are commonly employed for like purpose, may be associated with the tank 10 to maintain the charge of water therein at the desired temperature. The line 20 may discharge to waste or to other tanks and facilities, as may be deemed most expedient in a given instance, but it is in general desirable to provide a rinsing tank for the molds or containers 18 in convenient association with the defrosting tunnel, for which purpose an open-top tank 21 may be positioned at one side of and below the tank 10 to receive the outflow through the line 20, said tank 21 being provided with an outflow line 22 communicating through an upper tank portion to maintain a desired water level therein and discharging to waste, or to other agencies and apparatus, as the needs and associations of a given installation may indicate.

The apparatus thus far described is fully and automatically operable to accomplish the primary purposes of the invention. With the tank 10 associated with the delivery end of a conveyer in the manner shown and above set forth, and the lines 19 and 20 included in a hot water circulating system and arranged to maintain a level of hot water within said tank such as will cover the depressed portions of the slide-track 15,

open-top molds or containers 18 charged with frozen material and successively loaded on and in longitudinal alignment with the conveyer upper run are automatically and successively delivered to the shelf 13 in position to engage between the bars 17 for guided travel along the slide-track 15 in response to propulsive thrust developed through like delivery of subsequent units. As the charged molds or containers 18 longitudinally traverse the tank 10 they are lowered by the inclination of the slide-track 15 so that the sides and ends, as well as the bottoms, of said units are brought into contact with the hot water charge of the tank and held in such contact until engagement with the upward incline at the end of the slide-track 15 remote from the shelf 13 functions to lift the containers successively from the tank and onto the shelf 14, the openings 16 in said upwardly inclined slide-track portion permitting return to the tank 10 of water which might otherwise be trapped and pushed ahead of a mold or container onto the said shelf 14. During its transit through the tank 10, each mold or container 18 is so heated, as controlled by the temperature of the tank water and the speed of unit transit, as to disrupt and destroy the bond between the matrix and its contents, so that the units delivered to the shelf 14 may be lifted therefrom by an operator, inverted over a suitable receiver, and thereby discharged of their contents in symmetrical block form, as molded, without damage, delay, or the necessity for any direct handling of the food commodity.

While not essential to functioning of the improvement in the manner and for the purpose above described, it is desirable that the open-top units 18 be protected against contamination of their feed contents during their transit of the tank 10, to which end a removable and replaceable cover of the type shown in Figure 3 is advantageously provided. The cover element may be of any suitable specific form, construction, and relationship with the other elements of the device, and may conveniently be as illustrated in the drawing, wherein the tank-supporting legs 11 are extended a suitable distance upwardly beyond the tank upper margins and are rigidly interconnected by means of a rectangular frame 23 fixed to their upper ends to lie in a plane parallel with that of the shelves 13 and 14 and spaced upwardly above said shelves a distance sufficient to clear the units 18 in their travel thereunder, which frame defines a central aperture registering with the open top of the tank 10; the removable and replaceable cover element itself consisting of a flat plate 24 coextensive with the area defined by the frame 23 and formed with angularly-related side and end flanges disposed to telescope over and engage against corresponding portions of said frame. The heated water of the tank 10, and its contact with the chilled units 18, is productive of a concentration of water vapor above said tank and beneath the cover 24, which vapor tends to condense on the cover under surface and might undesirably drip on the exposed contents surface of the units 18 save for the provision of a drip baffle 25 associated with said cover. The drip baffle shown consists of a sheet of suitable material, bent to flattened V-shape, secured beneath and with its apex in registration with the longitudinal median line of the cover 24 to diverge laterally of and downwardly below said cover,

and sized to dispose its long margins outwardly beyond the bars 17 in overhanging relation with the tank portions between said bars and the adjacent tank sides and in position to lift through the central aperture of the frame 23. Water of condensation collecting on the under surface of the baffle 25 will move down the inclined baffle surfaces to the long margins thereof, before separating as drops from said surface, and hence will drip into the tank at either side of the slide-track 15, rather than into or upon the units 18.

Since many changes, variations, and modifications in the specific form, construction, and arrangement of the elements shown and described may be had without departing from the spirit of the invention, I wish to be understood as being limited solely by the scope of the appended claims, rather than by any details of the illustrative showing and foregoing description.

I claim as my invention:

1. Apparatus of the character described comprising, an open-top tank, means for circulating heated water through and at constant level within said tank, shelves extending outwardly from the opposite ends and above the water level of said tank to slidably receive and support charged molds, a slide-track merging at its ends with and oppositely inclined downwardly from said shelves to traverse said tank in submerged relation of its intermediate portion beneath the tank water level, guide bars fixed in diverging relation of their corresponding ends to upper surfaces of said shelves to connect between the latter in bridging relation with said tank and in aligned registration above the slide-track side margins, a cover removably and replaceably supported in suitably-spaced relation above said tank, and a drip baffle carried by said cover in registration of its drip margins with tank areas laterally exterior to the passage defined by said guide bars.

2. In a system for the processing of chilled food commodities, the combination with means for automatically and successively delivering charged chilled open-top mold units of means operable in response to such delivery to disrupt the frost bond between each mold unit and its contents, said latter means comprising a slide-track in alignment with said delivery means for the reception and guided support of mold units fed therewith by the pressure of successive mold deliveries thereto, and a depressed portion in said slide-track submerged beneath the surface of a constant-level, heated water bath a distance less

than the depth of the mold supportable thereby, and guide bars paralleling said depressed portion side margins engageable with unsubmerged upper margins of a mold on said slide-track.

3. Apparatus for disrupting the frost bond between a charged chilled open-top mold and its contents, comprising an open-top tank arranged for the circulation of heated water therethrough at maintained constant level therein, a slide-track traversing said tank in coplanar disposition of its opposite end portions above the tank water level as shelves extending oppositely and outwardly from said tank, an intermediate slide-track portion depressed beneath the tank water level a distance less than the depth of the mold supportable thereby, and spaced, parallel, guide bars end-fixed to and upstanding from the adjacent slide-track end portion surfaces and bridging said tank above the water level thereof in substantial alignment with the depressed slide-track portion side margins.

4. In apparatus for disrupting the frost bond between a charged chilled open-top mold and its contents having an open-top tank arranged for the circulation of heated water therethrough at maintained constant level therein, a slide-track traversing said tank in coplanar disposition of its opposite end portions above the tank water level as shelves extending oppositely and outwardly from said tank, an intermediate slide-track portion depressed beneath the tank water level a distance less than the depth of the mold supportable thereby, and spaced, parallel, guide bars end-fixed to and upstanding from the adjacent slide-track end portion surfaces and bridging said tank above the water level thereof in substantial alignment with the depressed slide-track portion side margins.
